(57) **CLAIM**

The ornamental design for an interface of an electrical connector, as shown and described.

DESCRIPTION

FIG. 1 is a top perspective view of an interface of an electrical connector, showing our new design; and, FIG. 2 is a top plan view thereof.

The broken line showing of the environment is for illustrative purposes only and forms no part of the claimed design.

1 Claim, 2 Drawing Sheets

FIG. 1

FIG. 2
